UNITED STATES PATENT OFFICE.

GEORGE W. GWINN, OF NEW YORK, N. Y., ASSIGNEE TO AUTOMATIC PACKING & LABELING COMPANY, OF DURHAM, NORTH CAROLINA, A CORPORATION OF NORTH CAROLINA.

BAG-FEEDING MECHANISM.

1,101,492.

Specification of Letters Patent. Patented June 23, 1914.

Application filed February 13, 1912. Serial No. 677,350.

To all whom it may concern:

Be it known that I, GEORGE W. GWINN, a citizen of the United States, residing at New York, in the county of New York and State of New York, have invented certain new and useful Improvements in Bag-Feeding Mechanisms, of which the following is a specification.

My present invention pertains to an improved bag-feeding mechanism, adapted more particularly for use in conjunction with automatic packing machines and the like. In automatic packing machinery as now commonly constructed and used, it is customary to place the bags upon the bag-holders by hand, thus entailing the expense of one or more attendants, generally unskilled and who, by reason of being unskilful, mutilate or destroy a number of bags and also fail sometimes for one cause or another to properly position a bag upon the holder.

It is an object of the present invention to produce a mechanism which will automatically withdraw the bags, one at a time, from a bag-runway or stacker, open up such bag and present the same to the bag-form or holder of the packing machine. By thus handling the bags, the packing machine may be operated at a higher speed than when the bags are hand-placed and, furthermore, there is greater certainty in operation, and with (usually) less expense.

The machine may be said, in general terms, to embody the following parts, operating to bring about the desired result: A combined runway and stacker in which the bags are placed on end or upon their bottom edge and urged forward by presser-40 plates toward the discharge end from which they are withdrawn, one by one, by a vertically-reciprocating and swinging member which opens up the bag and presents it in such condition to the bag-carrier, which in 45 turn grasps it and while still maintaining it open, carries it to the bag-holder or form of the packing machine. Working in conjunction with the bags in the runway is means for straightening up the bags, that 50 is, bringing them to a vertical position, and likewise means for temporarily relieving the forward bags, adjacent the discharge end, from pressure, so that the outermost bag

may be readily withdrawn without being subjected to undue strain.

A structure illustrating one embodiment of the invention is shown in the annexed drawings, wherein:

Figure 1 is a side elevation, partly in section, the parts being in that position in which a bag just withdrawn from the runway has been grasped by the bag-carrier, and the bag-withdrawer elevated; Fig. 2 a top plan view, the bag-withdrawer being broken away in part; Fig. 3 a vertical longitudinal sectional view, taken on the line 3-3 of Fig. 2, the bags being omitted from the runway, with the bag in the carrier or transerrer shown in section; Fig. 4 a transverse vertical sectional view on the line 4-4 65 of Fig. 3; Fig. 5 a perspective view of the bag-straightener and pressure-relieving mechanism; Fig. 6 a similar view of the bag-remover or withdrawer; Fig. 7 a horizontal sectional view, taken on the line 7-7 of 70 Fig. 3; Fig. 8 a vertical sectional view, on the line 8-8 of Fig. 9, the bag-remover being shown as descending and the bag-carrier in the act of carrying the previously-removed bag to a position where it may be 75 taken by the bag-holder or shape of the packing machine; Fig. 9 a horizontal sectional view on the line 9-9 of Fig. 8, the parts being in the same relative position as in said figure; Fig. 10 a transverse vertical 80 sectional view on the line 10-10 of Fig. 3, the parts being shown on a larger scale; Fig. 11 a sectional view on the line 11-11 of Fig. 10; Fig. 12 a diagram or chart of the various cams; Fig. 13 a vertical sectional view on 85 the line 13-13 of Fig. 14; and Fig. 14 a horizontal sectional view on a somewhat smaller scale, the parts being in the same position as in Fig. 13, and the carrier turret lock and the cams for opening and closing 90 the carriers being shown.

The mechanism as a whole is designed to operate in conjunction with a packing machine and will preferably be operated from the same source of power as that which operates the packer, or from a moving part of the packer, but inasmuch as the packer *per se* forms no part of the present invention only a fragmentary portion thereof is illustrated, just sufficient to bring out the correlation of the two structures.

In the drawings, 1 denotes a table or other fixed support, Figs. 2 and 4, and 2 a shaft extending up above the table and carrying a spider-frame 3, upon which are supported 5 the bag-forms or holders 4. Said shaft is adapted to be raised and lowered through suitable mechanism, and to be rotated step by step through gears 5 and 6. These parts belong to the packing machine and no further description or showing seems essential.

Secured to one edge of the table is a horizontal platform 7, best shown in Fig. 10, the connection being effected through a bracket 8 bolted to the table 1. Mounted upon the 15 platform is a bag magazine or runway, comprising a base 9, and two vertically-disposed sides 10 and 11, each preferably lined with a planished metallic plate, as 12. The runway is open at its rear end, the forward 20 end being partially closed by two vertically-disposed plates or lips 13 and 14, forming a restricted mouth, somewhat narrower than the width of the bags, designated by 15.

To press the bags forward in the runway 25 toward the mouth, two presser-plates are employed, the two being alike in construction and operation; consequently, a description of one will suffice, the corresponding parts being similarly lettered with the addition of the exponent *a*.

Extending upwardly and outwardly from the side wall 11 is a bracket 16, to which is secured a horizontally-disposed rail 17, having mounted thereon a slide 18, to the 35 upper edge of which is pivoted to swing in a vertical direction a push-plate 19, having a handle 20, see Fig. 10. To a lug 21, extending out from the slide there is secured a cord or cable 22, which extends forward 40 up and over a pulley 23, carried by a bracket 24 secured to rail 17, said cord thence passing rearwardly over a pulley 25 and having a weight 26 secured thereto. The tendency of the weights 26 and 26^a is to draw the 45 slides 18 and 18^a forward and consequently to push the bags toward the discharge end of the runway. The purpose of having two push-plates is to insure a proper feed of the bags, for while one plate is acting the attendant may be filling the runway between the forward active plate and the rear plate, and thereafter as the bags become depleted 50 forward of the forward plate, swing said plate upwardly and move it and its slide 55 rearwardly, permitting the other slide to become in effect the forward slide. By arranging the slides upon opposite sides of the runway either one may be withdrawn from operative relation with the bags and moved 60 rearwardly independently of the other.

The bags are withdrawn from the runway one at a time and the means provided for doing this comprises a plunger, see Figs. 4 and 6, having a relatively sharp lower end 65 27, a flat rear face 28, and a forward out-

wardly-inclined face 29. In other words, the plunger increases in size upwardly from the lower sharp edge, the enlargement extending forwardly from the rear vertical face. The plunger is secured to an arm 30, 70 which in turn is secured to the upper end of a slide 31, which is movable through a swinging guide 32, pivoted at its upper end to the upper end of a fixed bracket or post 33. An oscillating movement is imparted to the guide 32 through an arm 34 fixed to the lower end thereof to which in turn there is pivotally connected a link or rod 35, see Figs. 7 75 and 13, the rear end of the rod being pivotally connected to the upper end of a rocker arm 36. Said rocker arm is fulcrumed upon a shaft 37 carried by depending arms 38 and 39, see Fig. 10. The lower end of the rocker arm 36 carries a bowl 40 which works in a cam groove 41, formed in one face of a cam member 42 splined to and rotatable with a driven shaft 43.

To effect a reciprocation of the slide 31, through the slideway, there is secured to the lower end of the slide a link 44 which in turn is pivoted to the forward end of a relatively long arm 45 which extends forward from a collar or sleeve 46, fulcrumed on shaft 37. An arm 47 extends downwardly 95 from collar 46, carrying at its lower end a bowl 47^a adapted to work in a cam groove 48. This mechanism imparts to the bag-withdrawing plunger a compound vertical and swinging movement, the lower end of the 100 plunger swinging rearward when it is fully elevated, see Figs. 1 and 3, until it comes to a vertical position, Fig. 8, when it descends and passes downwardly into the bag, Fig. 13. Owing to the shape of the cam 41 during 105 this downward movement no swinging motion of the guide 32, and consequently of the plunger, takes place; so, too, when the plunger reaches its limit of downward movement cam 48 becomes for the time being inactive and at the same time, through the 110 action of cam 41, a forward movement of the plunger takes place, and said plunger being in a bag draws the same outwardly from the runway (Fig. 13) between the lips 115 13 and 14. The plunger carries the bag forward to a bag-carrier or transfer mechanism, where it is grasped and while so held the plunger is withdrawn therefrom, moving upwardly from the dotted-line position 120 shown in Fig. 13 to the position shown in Figs. 1 and 4.

The upper edge of the forward face of the bag will preferably be somewhat lower than the opposite side, see Fig. 4, so that the plunger when it is thrown rearwardly preparatory to the descent thereof will clear the forward bag face and come into contact with the inner side of the rear face, or the bag liner, if a double-walled or lined bag be em- 125 130

ployed. Thus the plunger, owing to its position, and to the forward wedge-shaped face thereof, will always enter the bag and this without damage thereto. To push downwardly the bag or bags standing immediately behind the one being withdrawn, I secure to the rear face of the plunger a push-plate 49, see Fig. 6, which contacts with such bags and serves to push the same downwardly so that they will stand on the bottom of the runway and be in position to properly function with the plunger as it acts to successively withdraw the same. To relieve the bags momentarily from pressure as the outermost one is being withdrawn from the runway, and to also straighten up the bags or cause them to stand vertically in the runway as they approach the plunger, so that the latter may properly function with the same, suitable automatic mechanism is employed.

Mounted in suitable guideways 50, 51, carried by the underside of the platform 7, see Fig. 10, is a slide 52, said slide being reciprocated through the agency of a link 53, connected to lugs 54 extending down from the rear end of the slide, the opposite end of the link being connected to the upper end of a rocker-arm 55, fulcrumed upon shaft 37, the lower end of the rocker arm carrying a bowl 56, which works in a cam groove 57.

The forward end of the slide is provided with a centrally-disposed slot 58, see Fig. 7, and also with two laterally projecting wings 59 and 60. Pivoted to the under face of lug 59 (see Fig. 5) is a lever 61 of the first order, while pivoted to the wing or lug 60 is a second lever 62 of the same order. The inner ends of said levers overlap and are pin-jointed, one being slotted so that they may swing past a line passing through their pivotal points; in other words, they form a toggle which may be thrown to one or the other side of the center line. Extending through and pinned to a hub 63 formed on the outer free end of lever 61 is a vertically-disposed rod 64, and pinned to the rod is a frame or casting 65, the vertically-disposed member of which carries two beveled or tapering fingers 66 and 67. A second frame 68 is pivotally supported on rod 64, said frame being provided with a single beveled finger 69 at its upper end. A spring 70 tends to rotate frame 68 and consequently to throw finger 69 inwardly, such inward movement being limited by a stop lug 71, carried by a hub 72 pinned to rod 64. Similar parts are carried by or supported upon the outer end of lever 62, the parts being similarly lettered with the addition of the exponent α .

The lower ends of the rods 64 and 64 α are connected by a coiled spring 73 which acts to hold the levers 61 and 62 in one or the other of the two positions to which they may be

moved; or, in other words, to hold the toggle formed by said levers to one or the other side of the center line of the toggle. The shifting of the levers is brought about by the movement of the slide 52, carrying the levers 70 into contact first with one and then with the other of two pins 74 and 75, best shown in Figs. 3 and 13, which extend down from the under face of platform 7.

Cam 57 is so formed and timed that after 75 a bag has been withdrawn by the plunger the fingers will stand in the position shown in Fig. 14, that is, entirely withdrawn, at which time slide 52 is moving rearwardly and the toggle has come into contact with pin 75, 80 and has been straightened and is about to be thrown forward by spring 73. As the toggle is moving to its center line or straightened position, frames 65 and 65 α are swung outwardly so as to withdraw the fingers 66 and 85 67 and 66 α and 67 α from between the bags, and when the parts reach the positions shown in Fig. 14 the push-plate will act to force the bags in the runway forwardly against the lips 13 and 14. Upon a further 90 rearward movement of the slide the toggle will be broken by pin 75, and the outer ends of levers 61 and 62 will swing inwardly, thereby carrying fingers 69 and 69 α between the bags at the upper portion or end thereof, 95 see Fig. 2. When the movement of slide 52 is reversed, said fingers, being carried forward to a slight extent while still between the bags, have a tendency to push the upper portions of the bags forward, or to 100 straighten them up so that the mouth of the outermost bag will be directly against the lips 13 and 14, beneath the plunger. Inasmuch as these fingers are carried by the spring-urged frames there is no tendency to 105 tear the bags, as the slide moves forward, the fingers swinging outwardly if undue pressure should be exerted. The fact that the lower ends or bottoms of the bags are formed with folded-over portions, and consequently 110 present a slightly greater thickness than at the top, makes it desirable to employ the mechanism just set forth. Upon a further forward movement of slide 52, the toggle comes into contact with pin 74, is again 115 broken and the fingers 66 and 67 and 66 α and 67 α are thrown in between the bags as indicated in Fig. 9.

The side walls of the runway are formed with suitable openings 76 and 77 through 120 which the lower fingers 66 and 66 α may pass. At such time the plunger is beginning to descend, and in order to relieve the bag which is to be withdrawn from undue pressure against lips 13 and 14 and possible injury, the cam 57 is so timed as to carry the slide 52 and consequently fingers 66, 66 α , 67 and 67 α rearwardly to a slight extent, while still in their inward position. Such movement, as will be readily appreciated, 125 130

takes the pressure of push-plates 19 and 19^a off of those bags which are forward of the fingers and adjacent the mouth of the runway. This permits the plunger to descend 5 and withdraw the bag without fear of injury. Upon further rearward movement of the slide, the toggle is straightened, the fingers withdrawn and the push-plates again allowed to act to advance the bags along 10 the runway. The same cycle of operations is repeated.

The devices or mechanism for transferring the bag from the plunger to the packing machine will now be described. Secured to and extending outwardly from platform 7, is a bracket 78, in the outer end of which is mounted a vertically-disposed shaft 79, said shaft having splined thereto, below the bracket a sprocket-wheel 80 and a 15 locking plate 81, provided with peripheral notches 82. The upper part of the shaft has splined to it a turret or frame having four radially-disposed arms 83, the outer end of each arm carrying two horizontally-arranged, substantially shaped frames 84 and 85. Each end of each arm of the frame is provided with a hub or boss 86, and parallel, vertically-disposed rods or shafts 87 and 88 are mounted in the bosses. To the lower 20 end of shaft 87 is secured a lever 89, and also a notched arm or jaw 90. A lever 91 is secured to the lower end of shaft 88, the ends of said lever and lever 89 overlapping and being connected to each other by a machine 25 screw 92, which passes upwardly through an elongated slot in lever 89 and is screwed into lever 91. A roller 93 is carried at the lower end of the screw. Shaft 88, adjacent to its lower end, has also secured to it a notched 30 arm or jaw 94. Similar arms or jaws 95 and 96 are, respectively, connected to the upper ends of shafts 87 and 88, and each shaft has wound about the same a coiled spring 97, said spring being secured at one end to the 35 shaft and at its opposite end to the frame. Said springs tend to rotate the shafts in such direction as to close the jaws, or in other words to cause them to approach each other. A stop arm 98, formed as an extension of the 40 jaw 95, Fig. 2, coacts with a screw 99, mounted in a lug 100, extending upwardly from arm 83, and acts to limit the approach 45 of the jaws.

Shaft 79, and consequently arms 83, are 50 rotated by means of a sprocket-chain 101, which passes about sprocket 80 and a sprocket 102, Fig. 4, secured to shaft 2, and inasmuch as shaft 2 is given a step-by-step 55 rotation, shaft 79 and the parts carried 60 thereby are likewise given such motion. Sleeved for oscillation upon the hub of the frame which carries the arms 83 is a casting comprising a sleeve 102^a, Figs. 3 and 14, and three arms 103, 104 and 105. Arms 103 and 65 104 are separated a distance slightly greater

than 90°, and the former is provided with an adjustable cam or striker 106, while the latter is provided with a similar member 107. Said members stand in the path of the rollers 93 and serve to open the jaws when 70 the parts come into line, as at the right in Fig. 14, and at the top, as in Figs. 2 and 7. These parts may be termed the jaw-actuating or opening mechanism, and to operate the same, that is, to oscillate it so as to cause 75 it to open one set of jaws and then another set, there is secured to the outer end of arm 105 a link or draw-rod 108, the opposite end of which is connected to the upper end of an arm 109, secured to shaft 37. Motion is imparted to said shaft through an arm or lever 110, secured at one end to the shaft, the opposite end carrying a bowl which works in a cam groove 111.

It is designed that the bag-grasping jaws 85 shall come to rest one set at a time in line with the discharge end of the bag runway and the plunger so as to be in position to grasp the bag which is on the plunger, and to insure the retention of the jaws in such 90 position I provide a locking pawl 112, fulcrumed upon bracket 78 and actuated by a bar or rod 113, pivoted thereto and to the lower member of rocker arm 55. The parts are so timed that as one set of bag-grasping 95 jaws 90, 94, 95 and 96 comes into juxtaposition with the plunger, the pawl will enter one of the notches 82 of the locking plate 81. At such time cam 107 will be brought to the position shown in Fig. 14 and the jaws 100 opened. When a bag has been withdrawn by the plunger and swung forwardly, the cam is moved away in a clockwise direction, thereby permitting the jaws to close under the action of springs 97, and grasp the then 105 distended bag by its opposite edges. The plunger then ascends from the bag and when fully elevated the pawl is withdrawn from the locking plate and the bag, still held in its distended position, is carried around to 110 a point beneath the bag form or holder 4. Said holder then descends and when within the bag the jaws are opened and moved away from the bag by the cam 106, which is then brought to such position as to open 115 the jaws. The bag is thus placed upon the holder or bag-form and being released from the jaws tends to close upon said holder, or, if preferred, the holder may be expanded as is usual in machinery of this class. The 120 bag-holder then moves upwardly and the jaws are then free to be turned another step forwardly.

From the foregoing it is thought that the 125 operation of the machine is sufficiently clear, it being understood, however, in so far as the generic invention is concerned, that the structure may be modified in many of its parts and details, and that the broader claims are to be read in such light. For 130

instance, the bags might be fed by gravity, in which case the push-plates would be done away with and yet the means for relieving the bag from strain as it is withdrawn would be just as efficacious. So, too, the bags might be withdrawn by a pneumatic device and the term "means" when employed as referring to the withdrawing mechanism is to be generically construed.

10 Having thus described my invention, what I claim is:

1. In a machine of the character specified, the combination of a runway for the bags; means for withdrawing the same therefrom 15 one at a time; means for relieving the bag being withdrawn from the pressure of the following bags; and means independent of said relieving means for throwing the open ends of the bags forwardly toward the front 20 end of the runway.

2. In a machine of the character specified, the combination of a runway for the bags; means urging the bags forwardly in the runway toward the discharge end thereof; means 25 for withdrawing the bags one by one; means acting as a bag is being withdrawn to move the other bags rearwardly in the runway; and means for throwing the open ends of the bags forwardly toward the discharge end 30 of the runway.

3. In a machine of the character specified, the combination of a runway for the bags; means for advancing the same along the runway; means for withdrawing the same therefrom 35 one at a time; means for relieving the bags being withdrawn from the pressure of the following bags; and means, independent of the advancing means, for throwing the open ends of the bags forwardly toward the 40 front end of the runway.

4. In a machine of the character specified, the combination of a runway for the bags; a pair of pivoted push-plates extending into the runway and urging the bags forwardly 45 therein toward the discharge end thereof; means for withdrawing the bags one by one from the runway; swinging fingers adapted to be moved into and out of the runway in rear of the bag to be removed; means for 50 actuating said fingers; and means for drawing the fingers rearwardly in line with the runway while they are in engagement with the bags.

5. In a machine of the character specified, 55 the combination of a runway for the bags; means urging the bags forwardly in the runway toward the discharge end thereof; means for removing the bags one by one; fingers arranged upon opposite sides of the 60 runway adjacent the discharge end; means for imparting an oscillating movement to said fingers to throw them into and out of the runway; and means for drawing said fingers rearwardly while they stand in the 65 runway.

6. In a machine of the character specified, the combination of a runway for the bags; means urging the bags forwardly therein; means for removing the bags one by one; fingers arranged upon opposite sides of the runway adjacent the discharge end thereof; means for oscillating the fingers to move the same into and out of the runway; means for drawing the fingers rearwardly while they stand in the runway in contact with the bags; and other fingers adapted to enter the runway as the first-named fingers are withdrawn, said other fingers contacting with the upper portions of the bags and acting to move said upper portions forwardly. 70

7. In a machine of the character specified, the combination of a runway for the bags; means for urging the bags forwardly in the runway; means for removing the bags one by one; a slide located below the runway; means for reciprocating said slide; a rod at each side of the runway; a frame secured to each rod; fingers extending inwardly from each frame toward the runway; a toggle connection between the lower ends of the rods, said toggle being carried by the slide; a spring acting to hold the toggle to one or the other side of its center line; and fixed pins co-operating with the toggle to throw the same as the slide is reciprocated. 80

8. In a machine of the character specified, the combination of a runway for the bags; means for urging the bags forwardly in the runway; means for removing the bags one by one; a slide located below the runway; means for reciprocating said slide; a rod at each side of the runway; a frame secured to each rod; fingers extending inwardly from each frame toward the runway; a toggle connection between the lower ends of the rods, said toggle being carried by the slide; a spring acting to hold the toggle to one or the other side of its center line; fixed pins co-operating with the toggle to throw the same as the slide is reciprocated; a second frame 100 pivoted on each rod; a finger extending inwardly from the upper portion thereof; a spring for each frame tending to draw the same inwardly toward the runway; and a stop lug secured to each rod, acting to swing the adjacent pivoted frame outwardly. 105

9. In a machine of the character specified, the combination of a runway for the bags; a plunger having a downward movement at the mouth of the runway and adapted to enter and remove the outermost bag; and means, positively movable toward and from the runway, for pushing the bags immediately in rear of the plunger downwardly into the runway to properly position the same. 110

10. In a machine of the character specified, the combination of a runway for the bags, means acting to push the bags forwardly therein; means for removing the bags 130

- one at a time from the runway; means for temporarily relieving the bags at the forward end of the runway from pressure; and means acting while the pressure is thus relieved for pushing such bags downwardly into their proper position in the runway.
5. 11. In a machine of the character specified, the combination of a runway for the bags; a plunger adapted to move downwardly into the outermost bag and to remove the same from the runway; and a push-plate carried by the rear face of the plunger, adapted to strike the upper ends of the bags immediately in rear of the plunger
10. 15. when the same is moved downwardly.
12. In a machine of the character specified, the combination of a runway for the bags; a plunger movable downwardly in line with the outermost bag in the runway; means for moving the plunger outwardly from the runway with a bag thereon; and a bag-transferring mechanism, comprising a plurality of bag-grasping devices adapted to be successively brought into operative relation with the bags on the plunger.
13. In a machine of the character specified, the combination of a runway for the bags; a plunger adapted to remove the bags one at a time from the runway; means for moving the plunger downwardly into the outermost bag and then outwardly away from the runway; a bag-transferring mechanism, comprising a rotatable member, and a plurality of bag-grasping devices carried by
18. 20. 25. 30. 35. said member, each grasping device comprising a plurality of normally-closed jaws; means for rotating said mechanism step by step; and means for opening the jaws of one device as it comes into position to grasp the bag held by the plunger, and to likewise open the jaws of the device which has previously grasped a bag and to release the bag held thereby.
14. In a machine of the character specified, the combination of a runway for the bags; a plunger adapted to remove the bags one at a time from the runway; means for moving the plunger downwardly into the outermost bag and then outwardly away from the runway; a bag-transferring mechanism, comprising a rotatable member, and a plurality of grasping devices carried thereby, each device comprising oppositely-disposed swinging jaws, and means for normally moving the jaws toward each other; means for moving said mechanism step by step; and a pair of cams to successively open the jaws of two of said grasping devices, whereby the device which comes into operative relation with the bag-transferring means will be first opened, and then closed, and the device which has already grasped a bag will likewise be opened.
15. In testimony whereof I have signed my name to this specification in the presence of two subscribing witnesses.
